Primary Examiner—Doris V. Coles*Assistant Examiner*—Linda Brooks*Attorney, Agent, or Firm*—Litman, Kraai & Brown L.L.C.[57] **CLAIM**

The ornamental design for a multi-panel display screen with rotatable frames, as shown and described.

DESCRIPTION

FIG. 1 is a perspective view of the multi-panel display screen with rotatable frames in accordance with the present invention.

FIG. 2 is a front elevational view of the multi-panel display screen with rotatable frames of FIG. 1.

FIG. 3 is a right side elevational view of the multi-panel display screen with rotatable frames of FIG. 1.

FIG. 4 is a top plan view of the multi-panel display screen with rotatable frames of FIG. 1.

FIG. 5 is a bottom plan view of the multi-panel display screen with rotatable frames of FIG. 1.

FIG. 6 is a left side elevational view of the multi-panel display screen with rotatable frames of FIG. 1; and,

FIG. 7 is a rear elevational view of the multi-panel display screen with rotatable frames of FIG. 1.
